UNITED STATES PATENT OFFICE.

JAMES W. DICKIESON, OF BROOKLYN, NEW YORK.

RULING-MACHINE.

SPECIFICATION forming part of Letters Patent No. 340,866, dated April 27, 1886.

Application filed September 12, 1885. Serial No. 176,912. (No model.)

To all whom it may concern:

Be it known that I, JAMES W. DICKIESON, of Brooklyn, Kings county, New York, have invented certain new and useful Improvements 5 in Ruling-Machines, of which the following is a full, clear, and exact description.

This invention relates to certain new and useful improvements in machines for ruling paper; and the object of my invention is to 10 provide a new and improved machine for producing diagonal lines at any desired inclination over the usual ruling.

The invention consists in the construction and combination of parts and details, as will 15 be fully described and set forth hereinafter, and pointed out in the claims.

Reference is to be had to the accompanying drawings, forming part of this specification, in which similar letters of reference indicate 20 corresponding parts in both figures.

Figure 1 is a side view of my improved ruling-machine, parts being broken out; and Fig. 2 is a plan view of the same.

The ruling-machine is, in general, of the 25 usual construction, the sheets I being placed on the endless bands A, passed over the roller A' and the pulleys C on the shaft D, then passing under the roller E above the roller B and upon the belt or apron F, which carries 30 them under the pens G, held in a bar, H, in the usual manner, and spaced the required distance. Cords J, passed over the roller E and shown in dotted lines in Fig. 2, hold the sheets I in the proper position on the apron 35 or belt F.

The table K, over which the bands A pass, is provided with two parallel transverse slots, L, through which screw-bolts M are passed, which are also passed through longitudinal 40 slots N in a gage, O, above the bands A. Nuts P are screwed on the lower ends of the screw-bolts M. A rod, Q, extends over the bands A directly in front of and parallel with the roller B, and is held at its ends in lugs or jaws 45 Q', projecting upward from the table. Sleeves R are pivoted on said rod Q, and on each sleeve R a sleeve, R', is formed transversely to the rod Q, and each sleeve R' is provided with a binding-screw, R'', for holding a rod, S, passed through the sleeve, and having its front end forked, and in which forked end a roller, T, is pivoted, having a rubber ring, T', held in its rim, the rubber projecting more or less from the rim of the wheel. Springs U are connected with the rear ends of the rods

S, and with a rod, V, held above the rod Q by arms V', projecting from standards W on the table.

The machine is driven in the usual manner. The operation is as follows: The sheets I, 60 which are ruled in the usual manner, are placed on the bands A and rested against the gage, so that their longitudinal or transverse edges are at a certain angle to the direction in which the sheets are carried by the bands A. The 65 rollers T immediately run on the sheets and hold them in place until they pass between the rollers E B, and are then held by the cords J, which hold them so that they cannot shift laterally. The sheets are thus moved under 70 the pens G, and thereby lines are drawn on the sheets diagonally to the other ruling. The gage O can easily be adjusted at any desired angle, to give the diagonal-inclined lines any desired angle to the usual ruling. The 75 springs U press the rollers T on the sheets, and the rubber rims prevent slipping of the sheets.

Having thus described my invention, I claim 80 as new and desire to secure by Letters Patent— 8c

1. The combination of the machine-table K, having a sheet-carrier, a diagonally-arranged gage above said carrier, and diagonally-arranged rollers in advance of the gage, with the rollers B E, through which the sheets pass 85 from the carrier, the endless apron F, the pens G above the apron, and the endless cords J, for holding the sheet in its gaged position for the action of the pens, substantially as set forth.

2. In a ruling-machine, the combination, 90 with a table and sheet-carrier, of pivoted rods carrying rollers above the sheet-carrier, and of a gage above the sheet-carrier, substantially as herein shown and described.

3. In a ruling-machine, the combination, 95 with a table and sheet-carrier, of the rod Q, the sleeves R on the same, the sleeves R' on the sleeves R, the rods S, passed through the sleeves R', and the rollers T in the ends of the rods S, substantially as herein shown and described. 100

4. In a ruling-machine, the combination, with a table and sheet-carrier, of the shaft Q, the sleeves R R', the rods S, the rollers T, the rod V, and the springs U, substantially as herein shown and described. 105

JAMES W. DICKIESON.
